UNITED STATES PATENT OFFICE

2,577,991

TELESCOPING HAIRDRESSING COMB

Esther E. Morris Zurndorfer, Chicago, Ill.

Application July 3, 1947, Serial No. 758,837

4 Claims. (Cl. 132—35)

1

The primary object of this invention is to provide a hair curling comb of the telescoping type and of an improved construction.

Another object is to provide the comb with improved means for projecting and withdrawing the comb and particularly the teeth thereof from and to within the holder, after the holder has been extended from the handle of the comb.

A further object is to provide a telescoping comb structure of a tubular shape for the specific purpose of curling the hair in a true tubular design of curl, and with improved means for extracting or withdrawing the comb teeth from the tubular formed curl without destroying the formed hair curl.

With the foregoing and other objects in view which will appear as the description proceeds, my invention resides in the combination and arrangements of parts and in the details of construction hereinafter described and claimed, it being understood that changes may be made within the scope of what is claimed, without departing from the spirit and intents of the invention.

An embodiment of the invention is illustrated in the accompanying drawing, wherein:

Figure 1 is a side elevation of this improved telescoping hair dressing comb showing the comb holder extended from the handle and the comb teeth projected from the holder.

Figure 2 is a longitudinal vertical section of Fig. 1 but showing the comb teeth withdrawn into the holder.

Figure 3 is a perspective view of the actuating member for the comb.

Figure 4 is an enlarged vertical transverse section taken approximately on the line 4—4 of Fig. 2.

Figure 5 is an enlarged vertical transverse section taken approximately on the line 5—5 of Fig. 1.

Referring to the drawing, the numeral 1 designates a tubular length which forms the handle as well as the closure for the comb and adapted for slidable adjustment in the handle 7 is a holder 8 for the comb 9.

For preventing turning of the holder 8 in the handle 7 a pair of diametrically opposed longitudinal slots 10 are formed in the inner periphery of the handle and engaged in each slot is a rib 11, said ribs extending the length of the holder 8 on the outer periphery thereof. The butt end of the holder 7 is closed by a cap 12 or the like.

For supporting the comb 9 in the holder 8, the actuating member 13 is provided, said member having end bearings 14 and 15 between which

2

the comb is mounted by the insertion of a pintle or rod 17 through the opening 18 in the bearing 14 and through the plurality of aligned elongated bearings 16 extending horizontally from one side of the comb at the top thereof, and through and into the opening 19 formed in the end bearing 15 of the comb actuating member 13.

After the comb 9 has been mounted in the member 13, said member with the comb in withdrawn position in respect to said member, is inserted in one end of the holder 8 and is secured therein by opposing pins 20 inserted through the wall of the holder and engaged in the annular groove 21, provided in the periphery of the bearing 15 of the member 13.

The bearing 14 of the member 13 is provided with an annular bead 25 for finishing engagement with the extending open end of the holder 8 and for preventing the holder from being entirely withdrawn from the handle 7 said handle is provided on its inner surface with a longitudinal groove 26 in which a projection 27 on the inner end of the holder is slidably engaged, said projection 27 abutting the end of said slot in the manner as shown in Fig. 2, when the holder 8 is extended from the handle 7.

When the holder 8 is pocketed in the handle 7 it is extended therefrom by the user grasping and pulling on the thumb and finger engaging part 24 and after the holder has been fully extended, right hand turning effort is given to the part 24 thereby turning the comb actuating member 13 and causing the pintle 17 to push against the bearings 16 of the comb 9, to project the teeth 22 thereof through the aligned apertures 23 formed in a longitudinal row in the wall of the holder 8.

The comb after withdrawal from holder 8 is then ready for use for combing the hair of the person user and for curling the hair strands. The comb teeth 22 when engaged in the hair strands are rotated for forming the curl after which the teeth 22 of the comb are withdrawn from the curl by turning the member 13 in the left hand or in counterclockwise direction. By turning said comb they are withdrawn into the holder 8 so that the holder can be slid from the formed hair curl without in any way affecting or disturbing the formed curl.

When the comb teeth are withdrawn into the holder 8 the holder can be readily slid into the handle 7 for its deposit in a handbag or other carrying device.

From the afore description of this invention,

it is apparent that an improved, efficient and inexpensive curl forming comb is provided.

What I claim is:

1. A telescoping hair dressing comb comprising, a tubular handle, a tubular comb holder slidably mounted in said handle, and actuating means in said holder for extending the teeth of the comb from the wall of the holder, said actuating means comprising a longitudinally extending member having end bearings between which the comb is mounted, said comb having an intermediately disposed elongated transverse bearing extending laterally of the plane of the teeth, and a pintle of the approximate length of said actuating means slidably engaged in said bearing at its ends in respective end bearings.

2. A hair dressing comb comprising a tubular handle, a recessed tubular comb holder longitudinally slidable in said handle, a comb in said holder having bearings extending substantially perpendicular to the plane of the teeth of said comb and actuating means in said holder having openings therein, and a pintle engaged in the bearings in the comb and in the openings in said actuating means for eccentrically projecting the comb teeth from said recessed holder when the actuating means is rotated.

3. A telescopic hair dressing comb comprising a tubular handle having a pair of diametrically opposed longitudinal slots formed interiorly thereof, a tubular holder slidable in and out of the handle having a plurality of outwardly extending guiding ribs slidable in the slots of said handle, an actuating member mounted in the tubular holder having end bearings thereon to permit rotation relative of said holder and a comb supported in said actuating member having a plurality of spaced, longitudinally aligned,

elongated bearings, and means extending through said aligned, elongated bearings extending laterally of the plane of the teeth interconnecting said comb to said actuating member, said comb being adapted when said actuating member is operated in a rotary manner to be projected teeth first from the holder thereof.

4. A telescopic hair dressing comb comprising a tubular handle, a holder axially slidable in and out of said tubular handle, an actuating member rotatably mounted in said holder, a comb pivotally mounted in said actuating member, said actuating member having a plurality of end bearings mounted in the holder to permit rotation thereof relative of the tubular handle, said comb on its upper end having a plurality of longitudinally aligned elongated bearings extending laterally of the plane of the teeth, and a longitudinal pintle extending through said elongated bearings disposed eccentric thereto to permit upon actuation of the turnable member relative dropping and lifting of said comb member.
